UNITED STATES PATENT OFFICE.

FRANK ZELEPUGAS, OF WORCESTER, MASSACHUSETTS.

SHINGLE-MAKING MACHINE.

1,311,633.

Specification of Letters Patent. Patented July 29, 1919.

Application filed July 25, 1918. Serial No. 246,702.

To all whom it may concern:

Be it known that I, FRANK ZELEPUGAS, a citizen of Russia, residing at Worcester, in the county of Worcester and State of 5 Massachusetts, have invented certain new and useful Improvements in Shingle-Making Machines, of which the following is a specification.

The primary object of the invention is 10 the provision of a machine adapted for cutting shingles from wooden blocks with great rapidity and requiring a minimum amount of attention on the part of the operator, the structure possessing great 15 strength and being easy and inexpensive to manufacture.

A further object of the invention is the provision of a shingle making machine adapted for successively cutting shingles 20 from a plurality of hand blocks, the latter being operated upon continuously until reduced to such a size as to be incapable of further use in the machine.

A further object of the invention is to 25 provide a shingle making machine designed for employing a horse for power and requiring the attention of only a single attendant in successively cutting a large number of shingles during the continued travel 30 of the horse.

With these general objects in view, the device consists of the novel combination and arrangement of parts hereinafter fully described and then claimed, as well as illustrated in the accompanying drawings in which like reference characters designate corresponding parts throughout the several views.

In the drawings:

40 Figure 1 is a top plan view of the device; Fig. 2 is a vertical diametrical sectional view thereof;

Fig. 3 is a vertical section of a part of the platform portion of the device; 45 Fig. 4 is a reduced bottom plan view of the cutting member;

Fig. 5 is a vertical transverse sectional view thereof taken upon line V—V of Fig. 6; and

50 Fig. 6 is a side elevation of the outer portion of the cutting member.

Referring more in detail to the drawings, a circular platform 10 is provided having a plurality of peripheral panels 11 carried 55 by radially arranged braces or spokes 12 attached to a central hub 13, it being under-

stood however that the said platform 10 is designed for stationary mounting and is preferably constructed in two halves or sections secured together by bolts 14. 60

Each panel 11 of the platform is provided with a radially positioned tapered socket 15 adapted for seating blocks of wood 16 therein, the said blocks being the proper size and shape for cutting shingles 65 therefrom. Wedges 17 are provided at the opposite ends of the sockets 15 for retaining the blocks 16 in position, while a spike 18 may also be employed with one of the wedges 17 and having a pointed head 19 for 70 engaging into the adjacent block 16.

A cutting member 20 in the form of a plank or handle is pivoted at one end to the hub 13 by means of a pin 21 mounted in the said hub and extending through a 75 disk 22 mounted upon the hub as well as extending through the adjacent end of the cutting member while a washer 23 is preferably provided upon the pin 21 between the disk 22 and the cutting member. A 80 blade 24 is secured laterally of the member 20 in a cutaway portion 25 of an enlargement or head 26 thereof, the edge 27 of the knife 24 projecting sufficiently beneath the head 26 to cut shingles of desired thickness 85 from the blocks 16 during the revolving of the cutting member 20 in the direction indicated by the arrow in Fig. 1 of the drawings.

Attaching hooks 28 are carried by the head 26 engaging beneath the opposite edges of 90 the cutter knife or blade 24 for holding the blade securely against opposite inclined shoulders 29 of the cutaway portion 25. Nuts 30 are provided upon the upper ends of the hooks 28 for securing the hooks in position. A guard plate 31 may be secured beneath the knife 24 and hooks 28 if found desirable at the bottom of the head 26 by means of bolts 32. A clevis hook 33 or similar attaching means is secured adjacent the outer 95 free end of the cutting member 20 to which a draft animal is adapted to be hitched for revolving the cutting member 20. A hand hold member 34 as well as a holding lever 35 is attached to the cutting member 20 adjacent its outer free end for convenience in grasping by the attendant in walking behind the draft animal during the operation of the device for guiding the knife 24 into proper contact with the blocks 16. 100 105 110

It will be seen that the manner of pivoting the cutting member 20 upon the pin 21

with the end of the cutting member seated upon a small washer 23, permits the cutting member 20 to be slightly shifted vertically while swinging around the circle in a plane 5 above and substantially parallel with the platform 10. The blocks 16 are securely maintained within the sockets 15 so that each successive block is engaged by the knife edge 27 during the travel of the cutting member 20 in the direction indicated by the arrow in Fig. 1 of the drawings. The cutting member 20 may continue to revolve for successive revolutions until the blocks 20 are reduced to a thickness slightly above the 10 head 19 of the spike 18 of each block and at which point the cutting operation is discontinued; and the remainder of the blocks removed by withdrawing the wedges 17 and spikes 18 while new blocks are then inserted 15 in the sockets 15. A large number of shingles may be quickly cut from the blocks 16 with only a little attention given by a single attendant who controls the oscillations of the cutting member 20 as well as drives the draft animal attached to the member 33 in a circular path around the platform 10.

What I claim as new is:—

1. A shingle cutter comprising a stationary horizontal circular platform having a central hub portion and provided with radially arranged tapered sockets in the top face thereof adjacent its periphery, adapted for receiving blocks to be cut, block retaining wedges and spikes carried by the platform at the opposite ends of each of said 30 35

sockets, and a cutting member pivoted upon said hub portion projecting outwardly of the platform and arranged for swinging movement in a circular path above and substantially parallel with the platform during 40 the cutting operation.

2. A shingle cutting machine comprising a horizontal hub having a plurality of rigid radial spokes, a circular series of panels secured upon the outer end portions of said spokes having block receiving sockets in the upper faces thereof, means carried by each panel to retain blocks in said sockets, and a cutting member pivoted upon said hub and projecting outwardly of the panels adapted 45 50 for swinging movement in a circular path above and substantially parallel with the hub and panels during the cutting operation.

3. A shingle cutting machine comprising a horizontal stationary circular platform 55 having a hub and formed of a pair of semi-circular sections bolted together, each section including a plurality of rigid radial spokes having panels secured upon the outer end portions thereof, said panels having block receiving sockets in the upper faces thereof, means carried by each panel to retain blocks in said sockets, and a cutting member pivoted upon said hub and projecting outwardly of the panels adapted for swinging movement in a circular path above and substantially parallel with the hub and panels during 60 65 the cutting operation.

In testimony whereof I affix my signature.
FRANK ZELEPUGAS.
